LASTING MACHINE

Roscoe L. Hill, Norway, Maine, and Robert W. Ireland, Beverly, Mass., assignors to United Shoe Machinery Corporation, Flemington, N. J., a corporation of New Jersey

Application March 30, 1950, Serial No. 152,876

9 Claims. (Cl. 12—12.4)

1

This invention relates to lasting machines and more particularly, in some aspects, to machines for lasting the toe ends of shoes. The invention is herein shown as embodied in a machine the construction of which is in many respects such as found in bed-lasting machines of a well-known type exemplified by the disclosure of United States Letters Patent No. 1,018,477, granted on February 27, 1912, on an application of Matthias Brock, but it will be understood that it is not limited to this illustrative embodiment.

In the use of a machine of the above-mentioned type toe-embracing wipers are moved upwardly to wipe the toe-end portion of the upper heightwise of the last by movement of a double-acting treadle in one direction while they are held by the operator in effective wiping engagement with the upper through a hand lever, and thereafter by this hand lever they are further advanced and closed to wipe the marginal portion of the upper inwardly over an insole on the last. Each of the above operations may be repeated one or more times until conditions are satisfactory to the operator. After the wipers have thus wiped the upper inwardly over the insole they are forced down on the shoe bottom to apply compacting pressure to the overwiped marginal portion of the upper by reverse movement of the double-acting treadle. It has been found advantageous for the operator thus to have full control of the wipers in wiping it heightwise of the last and inwardly over the insole, so that he may observe the results as the lasting operation progresses and may subject the upper to such special treatment as may be required. After the inward wipe, however, the application of increased pressure to the upper is not a critical operation, but requires only the use of substantial force. The present invention accordingly provides novel means whereby the wipers are operated by power to apply their compacting pressure to the overwiped marginal portion of the upper, but are nevertheless under such full control of the operator as he has exercised heretofore in the wiping of the upper heightwise of the last and inwardly over the insole. For the purpose in view, the construction herein shown includes a fluid-operated piston which is rendered effective thus to force the wipers down on the shoe bottom by fluid pressure in response to reverse movement of the above-mentioned double-acting treadle after the wipers have been moved upwardly by the treadle and have been operated to wipe the upper inwardly. Preparatory to this action of the piston it is moved upwardly with the wipers

as the wipers are raised by the treadle to wipe the upper heightwise of the last. To relieve the operator, however, of the necessity of thus raising the piston by the treadle against resistance of the operating fluid, which would require the application of considerably greater force to the treadle and would render it difficult to control the wipers as desired, provision is afforded for raising the piston instead by fluid pressure but under such control that its upward movement is an idle movement without any effect on the wipers. More particularly, the construction shown includes a valve mounted in the piston for upward movement by the treadle to initiate the upward movement of the piston by the fluid and further movable upwardly thereafter with the piston to cause the piston to continue its upward movement and means affording provision for lost motion between the piston and the wipers to permit limited upward movement of the piston relatively to the valve, the piston having means arranged to cooperate with the valve to interrupt the flow of the operating fluid acting thereon within the range of such lost motion and thus to prevent any effective action of the piston on the wipers.

The above and other features of the invention, including various novel details of construction and combinations of parts, will now be more particularly described with reference to the accompanying drawings and thereafter pointed out in the claims.

In the drawings,

Fig. 1 is a view in front elevation of the machine in which the invention is herein shown as embodied, parts being broken away;

Fig. 2 shows a portion of the machine in left-hand side elevation;

Fig. 3 is a plan view of a portion of the machine, showing the toe wipers in positions over the shoe bottom;

Fig. 4 is a plan view of the right-hand portion of the machine, with parts broken away;

Fig. 5 is a section on an enlarged scale on the line V—V of Fig. 4;

Fig. 6 is a horizontal section through the piston associated with the toe wipers;

Fig. 7 is a vertical section on an enlarged scale on the line VII—VII of Fig. 6 with parts in the relation which they assume at the beginning of the upward movement of the toe wipers; and

Fig. 8 is a view similar to Fig. 7 with the parts in the relation assumed when the wipers are to be forced downwardly on the shoe bottom.

The machine includes a frame 2 on which is

pivotedly mounted at 4 for horizontal forward and rearward swinging movements a casting 6 the right-hand portion of which is supported on the frame but is broken away in Fig. 1, this casting corresponding to the part 3 shown in the above-mentioned Letters Patent. The casting 6 has mounted thereon means about to be described for supporting and controlling the heel end of the shoe in the toe-lasting operation, but without any heel-lasting means, and it will be understood that, similarly to the disclosure of the above-mentioned Letters Patent, it is swung rearwardly to an adjustably predetermined position when the machine is to operate on a right shoe and forwardly to the appropriate position when the machine is to operate on a left shoe.

Secured on the casting 6 in fixed relation thereto is another casting 8 which, through means hereinafter described, supports a heel band 10 for embracing and clamping the shoe about its heel end. The shoe is supported at its heel end on a jack 12 including a U-shaped member 13 one of the arms of which has a horizontal extension 14 guided for movements in directions lengthwise of the shoe in the casting 6. This extension has on its upper face rack teeth 16 engaged by a pinion 18 which is rotatable on the casting 8 and is turned by a hand lever 20 to effect a preliminary adjustment of the jack relatively to the heel band 10. A spring-pressed pin 22 on the hand lever is arranged to enter any one of a plurality of holes 24 in the casting 8 to retain the jack in adjusted position. The adjustment is preferably such that when the shoe is first mounted on the jack there is substantial clearance between its heel end face and the intermediate portion of the open band 10, as illustrated in Fig. 4. The left-hand arm of the U-shaped member 13 has mounted therein an upwardly extending post 26 which, similarly to the post 50 shown in Letters Patent No. 1,373,482, granted on April 5, 1921, on an application of Matthias Brock, can tip yieldingly in directions widthwise of the shoe against the resistance of opposed leaf springs on the member 13, one of these springs being shown at 28. Pivotedly mounted on a pin 30 in the post 26 to tip in directions widthwise of the shoe relatively to the post is a block 32 which is yieldingly controlled at its lower end by a spring-pressed pin (not shown) acting similarly to the member 19 shown in Letters Patent No. 1,128,303, granted on February 16, 1915, on an application of J. Fausse. In the construction herein shown there is pivotally mounted on the block 32 to swing about a pin 34 extending widthwise of the shoe a block 36 provided with an upwardly extending last pin 38 arranged to enter the usual spindle hole in the heel end of the last. A spring 40 connected to the post 26 and the block 36 tends to swing the block and the last pin 38 in a clockwise direction as viewed in Fig. 1 and holds them initially in positions determined by a stop screw 42 which is threaded in the block 36 and is arranged to bear against the upper end of the post 26.

The intermediate portion of the heel band 10 is secured to a holder 44 (Fig. 4) having a stem 46 held by a setscrew 48 in a yoke-shaped member 50. This member is secured indirectly to a plate 52 (Fig. 5) guided for movements in directions lengthwise of the shoe in the casting 8. Secured by screws 54 to the plate 52 to move therewith is a block 56, and in this block is slid-

ingly mounted a rod 58. Pivotedly mounted on a stud 60 on the left-hand end of the rod 58 is a crossbar 62 the opposite ends of which are connected by links 64 to slide bars 66. These slide bars are guided in recesses in the opposite ends of the yoke member 50 and at their left-hand ends are pivotally connected by pins 68 to levers 70 in locations between the ends of the levers. The inner ends of the levers are pivotally connected by pins 72 to blocks 74 fast on the opposite sides of the heel band 10 and their outer ends are connected to springs 76 which tend to swing their inner ends in directions toward the toe end of the shoe. Formed on the slide bars 66 are cam faces 78 arranged to be engaged by abutment faces 80 on the yoke member 50 to close the heel band inwardly against the sides of the shoe in response to lengthwise movements of the slide bars relatively to the yoke member, in which operation the levers 70 are swung about the pins 68 against the resistance of the springs 76. Such lengthwise movements of the slide bars are effected by moving the rod 58 toward the left relatively to the block 56 and the plate 52 to which the yoke member 50 is secured. Prior to this operation, however, the heel band is moved bodily lengthwise of the shoe to seat it firmly against the heel-end face of the shoe by moving the block 56 with the rod 58. For this purpose there is mounted on the rod, between the block 56 and a member 82 fast on the right-hand end of the rod, a compression spring 84. The member 82 acts through the spring 84 thus to move the block 56 until further bodily movement of the heel band is prevented by the shoe, after which the spring yields and further movement of the member 82 serves to move the rod 58 relatively to the block 56 to close the heel band. To operate the member 82 it has extending through it a rod 86 (Figs. 1 and 4) on which is mounted a compression spring 88 located between the member 82 and a plate 90 confined on the right-hand end of the rod by a nut 92. A head 94 formed on the left-hand end of the rod engages the member 82 to limit expansion of the spring. Portions of the rod and the spring are broken away in Figs. 1 and 4. The head 94 on the rod is connected by a link 96 to the upper end of a lever 98 which is pivotally mounted on the casting 8 and has a downwardly extending arm 100 engaged by one end of a push rod 102. The other end of this push rod is engaged and operated by a lever 104 pivotally mounted on a pin 106 on the casting 6. This lever is a power-operated lever, but the mechanism, including a cam, for operating it, is not herein shown, since it is of the same construction as mechanism provided heretofore in machines of the type shown in Letters Patent No. 1,018,477 for closing the heel band, as disclosed especially in Letters Patent No. 1,417,493, granted on May 30, 1922, on an application of Matthias Brock. The lever 104 corresponds to the lever 122 in the last-mentioned Letters Patent. It will be understood that the spring 88 is stronger than the spring 84 and may yield only in response to resistance of the shoe to the closing of the heel band. The lever 98 is operated against the resistance of a return spring 108 which assists in returning parts operated by the lever to their initial positions. That is, the member 82 and the rod 58 are returned by the head 94 of the rod 86, and the block 56 is returned by engagement of the crossbar 62 therewith.

The toe end of the shoe is supported on a toe

rest 110 mounted on the upper end of a vertically movable rod 112, this rod being supported at its lower end on a member 114 corresponding to the member 22 shown in Letters Patent No. 1,018,477. By means of a power-operated cam (not shown), which corresponds to the cam 180 shown in Letters Patent No. 1,417,493, the member 114 is moved upwardly to elevate the toe rest a predetermined distance in time relation to the operation of the heel band 10. In this manner the toe rest cooperates with the heel band in jacking the shoe and in positioning the toe end of the shoe heightwise in proper relation to the toe-lasting means. It will be understood that as the parts are shown in Fig. 1 the jacking of the shoe and the operation of the heel band have not as yet taken place.

When the heel band 10 is moved bodily as hereinbefore described to seat it against the heel-end face of the shoe it imparts a short lengthwise movement to the shoe to cramp the heel pin 38 in the spindle hole in the last, the heel pin swinging about the pin 34. This causes the heel pin to assist in holding the shoe firmly against any upward movement of its toe end in the toe-lasting operation. To afford additional insurance against any displacement of the shoe lengthwise in a heelward direction in the toe-lasting operation, mechanism is provided for positively locking the heel band against retractive movement. For this purpose a pair of pawls 116 (Figs. 4 and 5) arranged in staggered relation are pivotally mounted on a pin 118 supported on a block 120 which is secured to a top plate 122 on the casting 8. A spring 124 tends to swing the pawls downwardly, and for the purpose in view they are arranged to engage teeth 126 formed on a plate 128 which is secured by the screws 54 to the plate 52. Each pawl is provided with a roll 130 arranged to rest on the top face of a horizontal bar 132 slidably movable in a guideway in the block 120 and secured at its right hand end to the previously mentioned plate 90 which is carried by the rod 86. By engagement of the top face of the bar 132 with the rolls 130 the pawls are held initially upraised, as shown in Fig. 5, but as the bar is moved toward the left in the operation of applying the heel band to the shoe inclined faces 134 on the bar arrive in positions under the rolls 130 and permit the pawls to be moved downwardly into engagement with the teeth 126. It will be understood that in the return of the parts to starting positions the pawls are disengaged from the teeth by the inclined faces 134 to release the block 56.

The toe-lasting mechanism includes toe-embracing wipers 136 (Fig. 3) which are advanced and closed about the toe by a hand lever 138 in the same manner as in prior machines of the type shown in Letters Patent No. 1,018,477. Means provided for adjusting these wipers in various ways are also generally the same as heretofore in such well-known prior machines and need not be described in detail. The wipers and their adjusting means are supported by a bed plate 140 formed on the upper end of a slide 142 vertically movable in a guideway in the frame. Downward movement of the slide 142 is limited by engagement of the bed plate 140 with a stop plate 143 secured to the frame. For moving the wipers upwardly to wipe the toe end of the upper heightwise of the last the slide 142 is raised by a double-acting treadle 144 constructed and arranged substantially as heretofore except that, for the convenience of the operator, it is so

mounted as to extend diagonally toward the rear of the machine instead of parallel to the front of the machine. The treadle is fast on a rock-shaft 146 which carries a small lever 148 connected by a link 150 to another lever 152, this lever being connected to an upwardly extending link 154. Since the treadle-operated means for moving the wipers upwardly is associated, in the machine herein shown, with fluid-operated means hereinafter described for forcing them downwardly when they are over the shoe bottom, the link 154 is pivotally connected at its upper end to a cross-rod 156 (Fig. 2) the opposite ends of which lie in vertical slots 158 formed in the lower ends of a pair of links 160. At their upper ends these links are connected to a cross-rod 162 mounted in ears 164 formed on the lower end of the slide 142. Springs 166 connected to the cross-rod 156 hold it normally at the upper ends of the slots 158. Accordingly, depression of that arm of the treadle on which the operator rests the forepart of his foot serves to raise the slide 142 through the link 154, the cross-rod 156, the pair of links 160 and the cross-rod 162.

Secured to a bracket 168 on the frame is a vertical cylinder 170 in which is a piston 172 (Figs. 7 and 8) provided with a diametrically reduced portion 174 extending upwardly through a bore in a cylinder head 176 and having at its upper end a vertical slot 178 through which extends the cross-rod 162 (Fig. 2). Extending downwardly through the piston 172 from near the upper end of its reduced portion 174 is a bore 180 in which is slidably mounted a tubular valve 182 extending downwardly through a lower cylinder head 184. Threaded on the lower end of the valve is a coupling 186 (Fig. 2) and threaded in this coupling is a stem 188 by which the valve is connected to the cross-rod 156. Communicating with a port 190 in the cylinder head 176 is a tube 192 which leads from a pump 194 driven by an electric motor 195. The pump receives fluid, preferably light oil, from a reservoir or sump 198 and delivers it through the tube 192 to an annular chamber 200 in the cylinder 170 above the larger portion of the piston 172, the fluid in this chamber being thus maintained under pressure at all times. It will be understood that the excess fluid delivered by the pump returns to the sump past a spring-controlled relief valve (not shown). Initially the piston 172 is in its lowest position (Fig. 7) with a hollow cap 202 secured to its lower end in engagement with the cylinder head 184.

Formed in the larger portion of the piston 172 are four inclined ports 204 (Figs. 6 and 7) communicating at their lower ends with horizontal ports 206 in the piston, and these horizontal ports are at all times in communication with an annular chamber 208 in the valve 182. Four other horizontal ports 210 in the piston are arranged to communicate at times with this annular chamber, these ports being in communication through vertical ports 212 in the piston with the lower end of the cylinder 170 below the piston. The valve 182 has therein a bore 214 extending downwardly through it from near its upper end and communicating through ports 216 and 218 with an annular chamber 220 around the valve. At its lower end the bore 214 in the valve is in communication through the coupling 186 with a flexible tube 222 (Fig. 2) leading to the sump 198. To permit the escape of fluid which may leak past the valve 182 into the portion of the bore 180 above

the valve, this portion of the bore 180 is in communication through a port 214 and a flexible tube 226 with the sump.

Initially the valve 182 is so positioned relatively to the piston 172 that the ports 210 are closed by a circumferential portion 228 of the valve. When the operator, however, starts to move the treadle 144 in the direction to raise the slide 142 and the wipers, the valve 182 is immediately moved upward relatively to the piston 172 by the cross-rod 156 to the position in which it is shown in Figs. 7 to open communication between the annular chamber 208 and the ports 210. Such upward movement of the valve relatively to the piston is permitted by the slot 178 in the upper end of the reduced portion 174 of the piston, the cross-rod 162 being positioned initially below the upper end of the slot to provide for lost motion between it and the piston at the beginning of the movement of the treadle. Such upward movement of the valve beyond a predetermined position relatively to the piston is prevented by engagement of a diametrically enlarged portion 230 of the valve with the lower end of the piston, this portion of the valve being located within the cap 202. The opening of the ports 210 as above described establishes communication between the chamber 200 and the lower end of the cylinder 170 below the piston, and in view of the fact that the lower end of the piston and the cap 202 thereon have a greater effective area subject to upward pressure of the fluid than the area of the piston at the lower end of the chamber 200, the fluid immediately starts to raise the piston. As the operator continues to move the treadle to raise the wipers the valve 182 is moved farther upward to maintain its substantially the same relation to the piston and therefore the fluid continues to raise the piston. The slot 178, however, affords insurance that the fluid will not be effective at any time on the slides 142, since before the piston can be moved upward by the fluid relatively to the valve far enough to act on the cross-rod 162 the ports 210 are again closed by the portion 228 of the valve and such movement of the piston by the fluid ceases. This, moreover, is what results if the operator stops the movement of the treadle at any time in the course of the upward movement of the slide 142. The raising of the wipers is thus effected wholly by the treadle as heretofore in machines of the type illustrated in Letters Patent No. 1,018,477, thus enabling the operator to treat the toe end of the upper by the combined action of the treadle and the hand lever 138 on the wipers in the same manner as has been customary heretofore in wiping the heightwise of the last. At the same time, if the treadle is operated at the normal speed customary in toe lasting, the piston 172 is moved upward wholly by the pressure of the fluid and does not retard or render more difficult the operation of the treadle.

After the wipers have been moved upwardly by the treadle to wipe the upper heightwise of the last and have been operated by the hand lever 138 to wipe the marginal portion of the upper inwardly over an insole on the last, they are forced reversely downward to apply comparatively heavy compacting pressure to the overwiped marginal portion of the upper. To bring this about the operator starts to move the treadle 144 in the reverse direction by pressure of the heel end of his foot on the front arm of

the treadle. By reason of the resistance of the shoe to downward movement of the wipers the treadle thus acts through the link 154 to move the cross-rod 156 downward in the slots 158 against the resistance of the springs 166, thereby moving the valve 182 downward relatively to the piston 172 as far as permitted by engagement of the diametrically enlarged portion 230 of the valve with the cap 202 (Fig. 8). In this manner, as shown in Fig. 8, communication is established between the lower end of the cylinder 170 and the bore 214 in the valve through the ports 212 and 210, the annular chamber 220 and the ports 218. The pressure in the lower end of the cylinder is thus released, and accordingly the pressure of the fluid in the chamber 200, from which the fluid can no longer flow through the ports 204, becomes effective to force the piston downward and thereby to force the wipers downwardly with the required pressure on the marginal portion of the upper.

After the downward pressure has thus been applied by the wipers to the upper the operator moves to the treadle in the other direction by the ball of his foot to raise the wipers before retracting them from over the shoe by means of the hand lever. In this operation the cross-rod 156 is first moved to the upper ends of the slots 158, and thereafter the action is the same as in the raising of the wipers to wipe the upper heightwise of the last. That is, the wipers are actually raised by the treadle while the piston 172 is at the same time moved upward idly by the fluid acting on the lower end of the piston. After having retracted the wipers from over the shoe by means of the hand lever, the operator, by control of the treadle, causes the slide 142 and the parts thereon to be moved downward by gravity to their initial positions. To permit this it is, of course, necessary to release the fluid from the lower end of the cylinder 170. Such release of the fluid results from downward movement of the valve 182 to the same position relatively to the piston 172 as illustrated in Fig. 8, this downward movement of the valve being permitted by the slot 178 in the reduced portion 174 of the piston. That is, the piston being held stationary, the weight of the slide 142 and the parts thereon causes the cross-rod 162 to move downwardly in the slot 178 until the valve is in position to release the fluid below the piston, after which the piston is moved downward by the pressure in the chamber 200. When the parts finally assume their initial relation the ports 210 in the piston are again closed by the circumferential portion 228 of the valve.

The manner of operation of the machine having been fully explained in connection with the description of its construction, no further description of the operation is necessary for an understanding of the invention.

Novel features of the means herein disclosed for controlling the heel band are claimed in a divisional application, Serial No. 293,344, filed on June 13, 1952.

Having described the invention, what we claim as new and desire to secure by Letters Patent of the United States is:

1. In a lasting machine, wipers for wiping the marginal portion of an upper about the toe end of a last inwardly over the bottom of the last, said wipers being mounted for movement heightwise of the last to wipe the upper first in that direction, a member movable by the operator thus to move said wipers wholly by force applied there-

to by the operator, a fluid-operated member for moving the wipers reversely heightwise of the last by fluid pressure to increase their pressure on the upper after they have wiped it inwardly over the bottom of the last, said fluid-operated member being mounted to move heightwise of the last with the wipers when the wipers are moved by the operator in that direction, and valve means for applying to said fluid-operated member only such fluid under pressure as to move it idly heightwise of the last as the wipers are thus moved by the operator.

2. In a lasting machine, wipers for wiping the marginal portion of an upper about the toe end of a last inwardly over the bottom of the last, said wipers being mounted for movement heightwise of the last to wipe the upper first in that direction, a member movable by the operator thus to move said wipers, a fluid-operated member for moving the wipers reversely heightwise of the last by fluid pressure to increase their pressure on the upper after they have wiped it inwardly over the bottom of the last, said fluid-operated member being mounted to move heightwise of the last with the wipers when the wipers are moved by the operator in that direction, a valve for applying fluid pressure to said fluid-operated member to move it heightwise of the last as the wipers are thus moved by the operator, and means providing for lost motion between said fluid-operated member and the wipers to permit limited movement of that member heightwise of the last relatively to the wipers, said valve being constructed and arranged to interrupt the flow of fluid acting on said fluid-operated member in response to such movement of that member relatively to the wipers and thereby to prevent the fluid-operated member from acting on the wipers in the wiping of the upper heightwise of the last.

3. In a lasting machine, wipers for wiping the marginal portion of an upper about the toe end of a last inwardly over the bottom of the last, said wipers being mounted for movement heightwise of the last to wipe the upper first in that direction, a treadle movable by the operator thus to move said wipers, a fluid-operated member for moving the wipers reversely heightwise of the last by fluid pressure to increase their pressure on the upper after they have wiped it inwardly over the bottom of the last, said fluid-operated member being mounted to move heightwise of the last with the wipers when the wipers are thus moved by the treadle, and valve means controlled by the treadle for applying to said fluid-operated member only such fluid under pressure as to move it idly heightwise of the last as the wipers are moved in that direction by the treadle.

4. In a lasting machine, wipers for wiping the marginal portion of an upper about the toe end of a last inwardly over the bottom of the last, said wipers being mounted for movement heightwise of the last to wipe the upper first in that direction, a member movable by the operator thus to move said wipers, a fluid-operated piston for moving the wipers reversely heightwise of the last by fluid pressure to increase their pressure on the upper after they have wiped it inwardly over the bottom of the last, said piston being mounted to move heightwise of the last with the wipers when the wipers are thus moved by said member, a valve movable by said member for applying fluid pressure to said piston thus to move it heightwise of the last as the wipers are moved in that direction by said member, and

means providing for lost motion between said piston and the wipers to permit limited movement of the piston heightwise of the last relatively to the wipers, the piston being formed to cooperate with said valve to interrupt the flow of fluid for operating the piston within the range of such lost motion and thereby to render the piston ineffective on the wipers in the wiping of the upper heightwise of the last.

5. In a lasting machine, wipers for wiping the marginal portion of an upper about the toe end of a last inwardly over the bottom of the last, said wipers being mounted for movement heightwise of the last to wipe the upper first in that direction, a treadle movable by the operator thus to move said wipers, a fluid-operated piston for moving the wipers reversely heightwise of the last by fluid pressure to increase their pressure on the upper after they have wiped it inwardly over the bottom of the last, said piston being mounted to move heightwise of the last with the wipers when the wipers are thus moved by the treadle, a valve movable initially by said treadle for applying fluid pressure to said piston to move it heightwise of the last as the wipers are moved in that direction by the treadle and further movable by the treadle heightwise of the last with the piston to maintain such pressure on the piston, and means providing for lost motion between said piston and the wipers to permit limited movement of the piston heightwise of the last relatively to the wipers, the piston being formed to cooperate with said valve to interrupt the flow of fluid for operating the piston within the range of such lost motion and thereby to render the piston ineffective on the wipers in the wiping of the upper heightwise of the last.

6. In a lasting machine, wipers for wiping the marginal portion of an upper about the toe end of a last inwardly over the bottom of the last, said wipers being mounted for movement heightwise of the last to wipe the upper first in that direction, a treadle movable by the operator thus to move said wipers, a fluid-operated piston for moving the wipers reversely heightwise of the last by fluid pressure to increase their pressure on the upper after they have wiped it inwardly over the bottom of the last, said piston being mounted to move heightwise of the last with the wipers when the wipers are thus moved by the treadle, a valve in said piston movable by the treadle for applying fluid pressure to the piston thus to move it heightwise of the last as the wipers are moved in that direction by the treadle, and means providing for lost motion between said piston and the wipers to permit limited movement of the piston heightwise of the last relatively to the wipers, the piston having therein one or more passageways to be closed by said valve for interrupting the flow of fluid for operating the piston within the range of such lost motion and for thereby rendering the piston ineffective on the wipers in the wiping of the upper heightwise of the last.

7. In a lasting machine, wipers for wiping the marginal portion of an upper about the toe end of a last inwardly over the bottom of the last, said wipers being mounted for movement heightwise of the last to wipe the upper first in that direction, a member movable in one direction by the operator thus to move said wipers, a fluid-operated member for moving the wipers reversely heightwise of the last by fluid pressure to increase their pressure on the upper after they have wiped it inwardly over the bottom of the last, and a

valve movable by said first-named member upon movement of that member in the opposite direction to render said fluid-operated member thus effective on the wipers.

8. In a lasting machine, wipers for wiping the marginal portion of an upper about the toe end of a last inwardly over the bottom of the last, said wipers being mounted for movement heightwise of the last to wipe the upper first in that direction, a double-acting treadle movable in one direction by the operator thus to move said wipers, a fluid-operated piston for moving the wipers reversely heightwise of the last by fluid pressure to increase their pressure on the upper after they have wiped it inwardly over the bottom of the last, a valve for controlling the application of fluid pressure to said piston, and means for moving said valve to render the piston thus effective on the wipers by reverse movement of said treadle.

9. In a lasting machine, wipers for wiping the marginal portion of an upper about the toe end of a last inwardly over the bottom of the last, said wipers being mounted for movement heightwise of the last to wipe the upper first in that direction, a double-acting treadle movable in one direction by the operator thus to move said wipers, a fluid-operated piston for moving the wipers reversely heightwise of the last by fluid

pressure to increase their pressure on the upper after they have wiped it inwardly over the bottom of the last, said piston being mounted to move heightwise of the last with the wipers when the 5 wipers are thus moved by the treadle, a valve in said piston for controlling the application of fluid pressure to the piston, and means for moving said valve to render the piston thus effective on the wipers by reverse movement of said 10 treadle.

ROSCOE L. HILL,
ROBERT E. W. IRELAND.
